UNITED STATES PATENT OFFICE.

THOMAS L. PARKER, OF CHICAGO, ILLINOIS, ASSIGNOR TO THE STANDARD ELECTRIC MANUFACTURING CO., OF CHICAGO, ILLINOIS, A CORPORATION OF ILLINOIS.

SNAP SWITCH.

Application filed October 4, 1924. Serial No. 741,699.

My invention belongs to that general class of devices known as snap switches, particularly the type known in the trade as toggle snap switches, although certain features are applicable for push as well as toggle switches. The invention has among its objects the production of a device of the kind described which is simple, compact, convenient, durable, reliable, safe, efficient and satisfactory for use wherever found applicable. My invention has among its other objects the production of a device of the kind described that will operate easily, smoothly and quietly and with a quick or snap movement. It has among its further objects a device of the kind described consisting of a minimum number of parts, each of which may be economically constructed and the parts conveniently and economically assembled together in a completed device. Many other objects and advantages of the construction herein shown and described will be obvious to those skilled in the art from the disclosure herein given.

To this end my invention consists in the novel construction, arrangement and combination of parts herein shown and described and more particularly pointed out in the claims.

In the drawings wherein like reference characters indicate like or corresponding parts;

Fig. 1 is a front elevation of one type of switch with the face plate removed;

Fig. 2 is a sectional view taken substantially on line 2-2 of Fig. 1;

Fig. 3 is a sectional view taken substantially on line 3-3 of Fig. 1, the face plate shown in section;

Fig. 4 is a sectional view taken substantially on line 4-4 of Fig. 1;

Fig. 5 is a perspective view of the bracket arm plate;

Fig. 6 is a perspective view of the brush carrying member;

Fig. 7 is a perspective view of the rocker arm;

Fig. 8 is a view in elevation of one of the contact members;

Fig. 9 is an enlarged sectional view taken substantially on line 9-9 of Fig. 8; and

Fig. 10 is an enlarged sectional view taken substantially on line 10-10 of Fig. 8.

Referring to the drawings in which the preferred embodiment of the invention is

shown, 1 represents the bracket plate of suitable size, shape and material, and 2 a base or receptacle also of suitable size, shape and material, preferably of porcelain or like insulating material. The bracket plate 1 and receptacle 2 are secured together in any suitable manner, generally by means of screws, bolts, or the like, 3. In the drawings I have illustrated what is known as a toggle switch, the switch mechanism being controlled by means of the toggle lever or arm 5 projecting through the plate 1 to the exterior of the receptacle and through the usual face plate.

Referring particularly to Fig. 5, the plate 1 is provided with threaded holes 4 for engagement with the screws 3, and is stamped out to provide the integrally formed bracket arm members 7 which are bent up substantially as shown. An opening 6 is also stamped in the plate through which the toggle handle portion 5 extends. As shown, the bracket arms 7 are formed at their outer ends to provide shoulders 8 or stops for the brush carrying member 9 to be described. The arms are also preferably provided with studs 9 and 11 on the inside and outside, respectively, of the arms, and on the inside also provided with stops 13. These studs and stops are preferably formed integral with the arms by punching out metal from one side to the side where the stud or stop is required. I have indicated at 10, 12 and 14 how the metal is partially punched out so as to provide the projections 9, 11 and 13, it being understood that the punching is not sufficient to sever the material but merely to such an extent so that the stud or stops are sufficient length and remain integral with the bracket.

I have illustrated in Fig. 7 a perspective view of the rocker arm 16 which consists of a plate formed substantially as a yoke with the ends bent or turned to provide bearing portions 18 which are notched as indicated at 19 for engagement with the studs 9. The notches 19 provide open bearings facilitating the assembling. I prefer to provide a handle portion 5 on the arm 16, the same being of hard rubber, bakelite, fibre, or any equivalent insulating or non-conducting material. This handle portion may be secured to the rocker arm in any suitable manner, for example by molding the same on the extension 17 on the plate 16.

The brush carrying member is shown in perspective in Fig. 6 in which 20 represents a plate turned up at the ends as indicated at 21 to also provide a yoke, 22 being notches forming the bearings for engagement with the studs 11 at the outside of the bracket arms 7. The brush carrying arm is arranged for attachment to a spring 24, (see Fig. 3) which is connected to the rocker arm 16. As most clearly shown in Figs. 3 and 6, the member 20 is provided with a hook 23 for engagement with the spring 24 and plate 16 with the opening 25 for attachment of the opposite end of the spring 24. Obviously, when the device is assembled as shown in Fig. 3, when the handle portion 5 is pushed from one side to the other, the spring snaps past the pivotal centers thereby snapping the brush-carrying member from one side to the other, this movement, however, being limited by the shoulders or stops 8, movement of the rocker arm 16, or toggle lever as it may be termed, being limited by the stops 13. The brushes may be secured to the brush-carrying member in any suitable manner, the same as shown, consisting of bars 27 provided with contact member ends 28. 29 represents insulation and 30 plates arranged at either side thereof. The brush construction shown is mounted on the prongs or lugs 31 extending transversely outwardly from the arm portions 21. The construction and insulation is such that the brush slipped on the prongs 31 is entirely insulated therefrom. The insulation may be similar to that described in my Patent No. 1,389,213, or equivalent thereto. The ends 31 are then upset securing the brush parts in place.

In a single pole switch the brush is arranged one at one side of the brush-carrying members, the prongs on the opposite side being omitted. In a two pole switch the brushes are mounted at both sides, and obviously more than one brush may be carried at either side. With some types of switches the brushes are set at an angle, as for example, in a three-way switch, and they may be arranged reversed on opposite sides, as for example shown in Fig. 4, the contacts to be hereafter described being reversed. In other words for example, in a three-way switch the members 27 are so arranged that they are not in alignment, but at an angle to each other, so that pushing the toggle lever in one direction closes the circuit between the two contacts of the member and breaks the circuit through the other contacts. Pushing the toggle in the opposite directions breaks the circuit at the first mentioned member 27 and closes the same through the other member.

I have shown in Figs. 8, 9 and 10 a preferred type of contact, the same being in the form of a resilient brush adapted to fit

and embrace the portions 28 on the bar 27. As shown, 33 represent plates or the like preferably of conducting material secured to the recesses in the receptacle by means of screws 34 or the equivalent. Each part 33 is provided with an upstanding portion 35 and a transverse extending portion 36, preferably but not necessarily extending in the same direction as the portion 33. The conducting wire is secured and operatively connected with the contact by means of a screw 37. If desired, a prong or extending part 42 may be provided for preventing displacement of the wire when the screw 37 is turned down. Carried by the member just described, and preferably on the upstanding portion 35, is a brush or contact consisting of the plate 38 provided with the extending portions 40 spaced apart but with the ends 41 brought into proximity so as to yieldingly embrace and contact with the sides of 28 when brought in between the same. While 38 may be secured to 35 in any suitable manner, I generally prefer to secure the same to the integrally formed stop 39 which is flanged over at the outer end so as to overlie and permanently secure the contact or brush to the part 35. In this connection it may be mentioned that this lug 39 is preferably of such shape that there is no tendency for the brush portion to turn or become displaced and it will be noted by referring to dotted lines in Fig. 9 that the same may be reversed in position, the same being in one position on one side or end of the receptacle and in the reversed position on the other side. The devices are similar, the only difference being that on the one side portion 40 is as shown in full lines in Fig. 9 and as shown in dotted lines on the other side.

I have shown in Fig. 3 the face plate 43 in position over the device. It will be noted that the face plate is provided with an opening registering with the opening 6 in the plate 1. Preferably arranged between the plates is a cover member 44. I have shown this member mounted on the handle portion 5 and provided with indicating symbols 45. This cover member is generally made of fibre and may be slipped over the member 5, if desired a slight shoulder 46 being arranged to engage over the member and prevent its accidental displacement during shipping or installation. Obviously, when the member 5 is moved up or down, the proper indication will be shown through the opening in the face plate. These indications may vary with the particular type of switch, that shown in Fig. 1 being suitable for a single or double switch.

As most clearly shown in Figs. 1 and 5, plate 1 is provided with extended ends at with holes 47, 48 and 49. The holes 47 may be threaded to engage suitable screws for

securing the face plate 43 in place, while the holes 48 and 49 are arranged to receive screws or bolts for securing the switch in its receptacle, or where desired, the particular holes used depending upon the receptacle or box, it being the usual practice to arrange the switch in a metal or other box. As shown, portions of the porcelain are cut away adjacent the binding posts to permit attachment of the conducting wires to the binding posts.

While I have shown a single switch in piece, it is obvious that the same may be assembled in gangs, in which assembly each 15 usually has its individual porcelain receptacle, or, in some cases, one porcelain receptacle may be provided, arranged to receive any desired number of switch mechanisms. In a single pole switch the porcelain receptacle may be made smaller or narrower, as 20 obviously the space for the additional brush is not required. While the standard size of receptacle may of course be employed, it is generally preferred to construct the smaller 25 size for the single pole, as generally it is found advantageous where possible to have the receptacle substantially small.

The switch in operation is substantially quick, that is to say, that it has a particularly 30 snappy action, thereby preventing any 35 sparking or arcing. It will be noted that the device consists of a minimum number of parts, the movable parts not including the spring being substantially only two units and all of the units including the plate with 40 its integral formed brackets as well as the contacts are all practically of stamped construction resulting in economical manufacture. Assembly is very easy. The several brush contacts each require one screw while the plate and receptacle are secured together by two screws, the only riveting or upset-

ting is to secure the brush members on the prongs 31 and the contacts on the plates 35. The spring is easily hooked to its parts so that when the several parts of the units have been conveniently assembled, the units may all be assembled together in a most convenient manner.

Having thus described my invention, it is 50 obvious that various immaterial modifications may be made in the same without departing from the spirit of my invention; hence I do not wish to be understood as 55 limiting myself to the exact form, construction, arrangement and combination of parts herein shown and described or uses mentioned.

What I claim as new and desire to secure 60 by Letters Patent is:

1. In a switch of the class described, a brush carrier part consisting of a single flat piece of material bent at the ends to form a U-shaped piece with substantially parallel flat legs and formed with open bearings at the free ends thereof, spaced lugs bent outwardly from the free ends of said legs on said U-shaped piece, bars carried by said lugs having contact ends extending in opposite directions at each end of the bars, insulation upon opposite sides of the bars, and plates mounted on the lugs upon the outer sides of the insulation.

2. In a switch of the class described, a U-shaped rocker arm, an extension thereon 75 at its intermediate portion, bearing portions at the ends of the side portions of said rocker arm and disposed at right angles to the side faces of the body of the rocker arm, and formed in their outer ends with bearing receiving notches.

In testimony whereof, I have hereunto signed my name.

THOMAS L. PARKER.
